UNITED STATES PATENT OFFICE.

WILLIAM VANS COYOC, OF OXFORD, OHIO.

IMPROVED WASHING-MACHINE.

Specification forming part of Letters Patent No. 105,103, dated July 12, 1870.

To all whom it may concern:

Be it known that I, WILLIAM VANS COYOC, of Oxford, Butler county, State of Ohio, have invented certain new and useful Improvements in Washing-Machines; and I do hereby declare the following to be a full, clear, and exact description thereof, reference being had to the accompanying drawing, making a part of this specification.

My invention consists of certain improvements upon the washing-machine patented by John Dare, October 27, 1868.

In the accompanying drawing a perspective view of the machine embodying my invention is represented, a portion of the side being removed in order to exhibit the interior.

A is the tub for the reception of the clothes and apparatus; B, the wash-board, and C the rubbing-roller, which, by the provision of the ratchet D and pawl E is also a feeding-roller. The roller is operated by the swinging arms F, (hinged or pivoted at f,) levers G, and handle H. These parts are all embodied in the patent granted to John Dare, October 27, 1868.

In order to provide for the ready adjustment of the rollers for rubbing the clothes, I attach the apparatus C D E F G H to the frame by means of the side springs, I I, which are fastened to the tub A at i, and are inclosed by the

jaws K. The jaws K are fitted with tightening-screws L, by which the springs can be so adjusted that any required pressure can be brought to bear upon the rubbing-rollers.

The wash-board B, I perforate, as shown, to carry of the dirty suds, and a receptacle, M, receives the same. This may be emptied at any time through a suitable discharge-pipe.

The roller C being a feeding as well as rubbing roller is of necessity smooth-faced and but an imperfect rubber. In order to provide in connection with this roller C a form of roller better adapted for washing the clothes, I attach the fluted roller N immediately in the rear of the roller C, and have found by this combination of rollers that the work can be most perfectly accomplished.

I claim herein as new and of my invention—

In connection with a washing-machine constructed substantially as described, the fluted rubbing-roller N, side springs, I I, and tightening-screws L, as and for the purpose described.

In testimony of which invention I hereunto set my hand.

WILLIAM VANS COYOC.
